(57) **CLAIM**

I claim the ornamental design for a fluorescent tube protective case, as shown and described.

DESCRIPTION

FIG. 1 is an exploded perspective view of a fluorescent tube protective case, illustrating a two-tube embodiment, showing my new design;

FIG. 2 is a front elevational view of the invention;

FIG. 3 is a rear elevational view of the invention;

FIG. 4 is a left-side elevational view of the invention, illustrating the two-tube embodiment, the right-side elevational view being a mirror image thereof;

FIG. 5 is a top plan view of the invention;

FIG. 6 is a bottom plan view of the invention;

FIG. 7 is an exploded perspective view of the invention, illustrating a four-tube embodiment;

FIG. 8 is a left-side elevational view of the invention, illustrating the four-tube embodiment, the right-side elevational view being a mirror image thereof;

FIG. 9 is a top plan view of the invention, illustrating the four-tube embodiment; and,

FIG. 10 is a bottom plan view of the invention, illustrating the four-tube embodiment.

The broken lines showing fluorescent lighting tubes in FIGS. 1 and 7 are included for the purpose of illustrating the invention in use, and form no part of the claimed design.
